Fred C. Fischer
ATTORNEY

UNITED STATES PATENT OFFICE

CHARLES WEBER, OF NEWARK, NEW JERSEY, ASSIGNOR TO AMERICAN COIN SELECTOR CORPORATION, OF NEW YORK, N. Y., A CORPORATION OF NEW YORK

COIN CHUTE

Application filed February 11, 1930. Serial No. 427,535.

This invention relates to coin controlled vending machines and more particularly to a device for detecting coin substitutes when fraudulently used in such machines.

5 Numerous expedients have been used to detect the presence of iron slugs and other metallic coin substitutes; but it has been found that non-metallic substances such as cardboard may be effectively used as substitutes for coins in certain types of vending machines.

In such types of machines the coin usually serves as a clutch and the weight of the coin is immaterial. Consequently, any stiff material such as cardboard may be used to produce the clutching action in such machines.

It is an object of this invention to provide a device for preventing, in vending machines, the use of a coin substitute which is lighter in weight than the required coin.

A further object is the provision of means for detecting in vending machines the presence of coin substitutes containing magnetic metals.

25 A further object is the provision, in vending machines, of a device for ejecting improper coin substitutes so that they will not interfere with the subsequent operation of the machine when the proper coin is employed.

These and other advantages, which will later appear, are accomplished by the simple and practical construction and arrangement of parts hereinafter described and exhibited 35 in the accompanying drawings, forming part hereof, and in which:

Figure 1 represents a side view of the device mounted in a vending machine.

Figure 2 represents a view of the side of 40 the device opposite to that shown in Figure 1.

Figure 3 represents a front view of the device partially in section, taken on line 3—3 of Figure 1.

45 Figure 4 represents partial sectional views of certain portions of the device.

Figure 5 represents a perspective view of a portion of a channelled guide used in the device.

50 Referring to Figure 1, a vending machine

having a casing 6 is shown to have mounted therein a chute 7 adapted to receive coins through an aperture 8 in the casing 6. As the coin passes through chute 7 it follows an arcuate path and is directed onto a circular channelled track 9 lying in a vertical plane, and thence passes into the widened mouth 11 of the lower chute 10.

The proper coin, when inserted in aperture 8, acquires, while passing through chute 7, 60 momentum sufficient to carry it around the track 9 so that it may fall into chute 10.

Now, the track 9 has side walls of a height considerably less than the radius of the coin, and when a coin substitute of lighter weight 65 than the required coin is used in the machine, such substitute will be ejected as it partially traverses the track 9; for its weight and travel through chute 7 will be insufficient to give it the momentum necessary to carry it 70 entirely around the track 9 and into the mouth 11.

Such light weight coin substitutes travel about one-half the distance around the track and then fall laterally into the lower part of 75 casing 6.

When a coin substitute containing magnetic metal is used, such substitute will be attracted by a magnet 13 as the substitute enters the portion 12 of track 9, at which point 80 one wall of the track is cut away as shown in Figure 3.

The action of the magnet will be to draw the coin upwardly against the upper laterally projecting lip 14 or the lower laterally projecting lip 15, which lips deflect the coin sufficiently to cause it to fall downwardly into the lower part of casing 6.

From the above description it will be seen that I have provided a simple device for detecting the presence of fraudulent coin substitutes in vending apparatus, which device also is effective for ejecting such coin substitutes so that they will not interfere with the subsequent operation of the machine.

The foregoing disclosure is to be regarded as descriptive and illustrative only, and not as restrictive or limitative of the invention, of which obviously an embodiment may be constructed including many modifications with-

out departing from the general scope herein indicated and denoted in the appended claims.

Having thus described my invention, what I claim as new and desire to secure by Letters Patent, is:

- 3 1. In a vending machine, a coin chute having a looped portion intermediate its ends, said looped portion comprising a relatively shallow channel so that coins having less than 10 a predetermined weight may fall out of the channel.
- 15 2. In a vending machine, a coin chute, comprising an upper tube and a lower tube, said tubes being arcuate and rectangular in cross section, and a circular shallow channel connecting the tubes, so that coins having insufficient momentum will fall out of the channel.
- 20 3. In a vending machine, a coin chute comprising an upper tube and a lower tube, a shallow channel connecting the tubes, said channel being looped to form a substantially circular path for a coin so that coins having insufficient momentum will fall out of the channel.
- 25 4. In a vending machine, a coin chute, comprising an upper arcuate tube and a lower tube, and a channel connecting the tubes, the lower tube having a widened mouth communicating with the channel, said channel being looped to form an arcuate path so that coins having insufficient momentum will fall out of the channel before reaching the mouth of the lower tube.
- 30 5. In a vending machine, a coin chute comprising an upper arcuate tube and a lower tube, a channel connecting the tubes, said channel being looped to provide an arcuate path, a magnet positioned adjacent the junction of the channel and the upper tube to attract coins containing magnetic metals, and lips on the tubes to deflect coins attracted by the magnet, said channel having a portion of its outer wall cut away so that coins attracted by the magnet may fall out of the channel.
- 45 45. This specification signed this 22nd day of January, 1930.

CHARLES WEBER.
